(57) **CLAIM**

The ornamental design for a saw plate, as shown and described herein.

DESCRIPTION

FIG. 1 is a perspective view of the saw plate of the present invention with a saw attached shown in phantom.

FIG. 2 is a perspective view of the saw plate of the present invention.

FIG. 3 is a top view of the saw plate of the present invention.

FIG. 4 is a bottom view of the saw plate of the present invention.

FIG. 5 is a first side view of the saw plate of the present invention.

FIG. 6 is a second side view of the saw plate of the present invention.

FIG. 7 is a first end view of the saw plate of the present invention; and,

FIG. 8 is a second end view of the saw plate of the present invention.

The broken lines shown in the drawings are included for the purpose of illustrating environmental structure and form no part of the claimed design.

1 Claim, 6 Drawing Sheets
